G. L. McCAIN,
PUMP DRIVING MECHANISM,
APPLICATION FILED NOV. 30, 1917.

Patented June 28, 1921.

UNITED STATES PATENT OFFICE.

GEORGE L. McCAIN, OF DETROIT, MICHIGAN, ASSIGNOR TO PACKARD MOTOR CAR COMPANY, OF DETROIT, MICHIGAN, A CORPORATION OF MICHIGAN.

PUMP-DRIVING MECHANISM.

1,382,997.

Specification of Letters Patent. Patented June 28, 1921.

Application filed November 30, 1917. Serial No. 204,755.

To all whom it may concern:

Be it known that I, GEORGE L. McCAIN, a citizen of the United States, and resident of Detroit, Wayne county, State of Michigan, have invented certain new and useful Improvements in Pump-Driving Mechanism, of which the following is a specification.

This invention relates to pump driving mechanism and particularly to such mechanism as used in connection with the water pump of a hydrocarbon motor.

One of the objects of the invention is to provide an efficient driving mechanism for a water pump together with a packing for the pump shaft that will automatically take up wear.

Another object of the invention is to provide a hydrocarbon motor with a water pump and a shaft extending from the motor casing to the pump impeller together with means to prevent leakage along the shaft both from the motor casing and from the pump casing.

Other objects of the invention will appear from the following description taken in connection with the drawings which form a part of this specification, and in which—

Figure 1 is a sectional view of a pump driving mechanism embodying the invention; and

Fig. 2 is a transverse section on the line 2—2 of Fig. 1.

Referring to the drawings, 10 represents one of the walls of a hydrocarbon motor crank casing or base and 11 is a pump casing which is shown as detachably connected to the motor casing as by a series of bolts, one of which is shown at 12. The pump impeller 40 is shown at 13 as mounted in the pump casing, 14 indicates the inlet to the casing, and 15 is the circumferential chamber at the periphery of the impeller and which connects with the outlet from the casing.

The impeller is driven by a shaft 16 to which it is connected as by the nut 17, and this shaft is mounted in alined bearings in the motor and pump casings. In the pump casing the bearing is plain as at 18 and in the motor casing a ball bearing 19 is provided for the shaft.

It is desirable that lubricant shall not escape from the motor casing and for this purpose a throw-off ring 20 is mounted on the shaft 16 immediately beyond the bear-

ing 19, this ring being provided with two flanges 21 from which the lubricant is thrown into a recess 22 and from there drained back into the crank case through a passage 23.

Leakage of water from the pump along the shaft 16 is prevented by a packing ring 24 which surrounds the shaft and is arranged in a recess 25 somewhat larger than the shaft. A sliding sleeve 26 also surrounds the shaft 16 and is arranged in a cylindrical extension 27 of the motor casing 10, this extension surrounding shaft 16 and practically covering the latter between the motor casing 10 and the pump casing 11. The sleeve 26 extends into the recess 25 and in contact with the outer end of the packing ring 24 and a spring 28 yieldingly presses the sleeve in contact with the ring. One end of the spring 28 rests against a flange 29 formed on the sleeve 26 and the other end rests against the wall 30 of the inner end of the extension 27.

The sleeve 26 is formed with one or more radial fingers or keys 31 which may extend from the flange 29, and these fingers are arranged to slide in keyways 32 formed lengthwise in the extension 27. Thus the sleeve 26 is prevented from turning as it slides relative to the shaft 16 and the spring 28 holds it in close yielding contact with the packing ring 24.

It will be understood that the pump casing may be readily removed from the motor casing and at the same time the packing ring 90 may be renewed and the parts replaced as before.

It will be understood that my invention is not limited to the details of construction shown and other forms may be used without departing from the spirit or scope of the invention.

Having thus described my invention, what I claim and desire to secure by Letters Patent is:—

1. In a pump driving mechanism, the combination with a pump casing, an impeller therein, and a shaft connected to the impeller, of a compressible packing ring around the shaft, a sliding sleeve in contact with the packing ring and keyed to prevent turning with the shaft, and a spring bearing against the sleeve and a non-rotating wall to compress said packing ring.

2. In combination with a driving element 110

and a driven element, a common shaft connecting said elements, means for preventing the passage of fluid from each of said elements along said shaft in either direction 5 comprising a bearing adjacent each element on said shaft, a common inclosing member extending from one bearing along the shaft toward the other bearing to form an inclosed chamber, means on the shaft adjacent 10 one bearing for interrupting and diverting the fluid carried along the shaft, means at the other end of said chamber for packing the shaft and a spring interposed between said parts and exerting pressure upon said 15 packing to maintain the latter in operative position.

3. In combination with a fluid impelling element, a driving element, a common shaft for said elements, a casing for each element 20 in which said shaft is mounted, said shaft

having a bearing in each casing, a shell extending from one casing and longitudinally of the shaft to a point adjacent to the other casing and providing a chamber intermediate said bearings, a member carried by 25 said shaft for interrupting and diverting the fluid passing from the driving element along the shaft, said member being located at one end of such chamber, a sliding sleeve located at the other end of the chamber, such 30 sleeve having means of engagement with said extended shell to prevent rotation of the former, a compressible packing in said impeller element casing, said sleeve having contact with said packing and a spring with- 35 in said chamber bearing against said sliding sleeve.

In testimony whereof I affix my signature.

GEORGE L. McCAIN.
